UNITED STATES PATENT OFFICE.

FRANK A. SCHULTZ, OF CHICAGO, ILLINOIS, ASSIGNOR TO PELOUZE MANUFACTURING CO., A CORPORATION OF ILLINOIS.

AUTOMATIC SWITCH FOR FLAT-IRONS.

1,306,723.

Specification of Letters Patent. Patented June 17, 1919.

Application filed March 17, 1917. Serial No. 155,426.

To all whom it may concern:

Be it known that I, FRANK A. SCHULTZ, a citizen of the United States of America, and a resident of Chicago, county of Cook, 5 and State of Illinois, have invented certain new and useful Improvements in Automatic Switches for Flat-Irons, of which the following is a specification.

This invention relates mainly to electric 10 flatirons and kindred implements, and particularly to current controlling means therefor, but some features of the invention are broadly applicable to the current switching means of many kinds of electrical devices, as 15 will be understood from the following description and claims.

The main objects of this invention are to provide an improved form of current-controlling means or switch for hand-operated 20 implements; to provide such means adapted for automatic or partly automatic operation, controllable at the will of the operator while the implement is in use; to provide automatic switching means on an ironing device 25 adapted to facilitate control of the heat source and particularly for actuation by tilting the iron either while in use or upon resting the same so as to open the circuit and cut off the supply of heat thereby; to 30 provide an improved form of switch and mounting therefor; and to provide an improved form of switch-controlling lock or latch, and latch-tripping means for releasing the switch.

An illustrative embodiment of this invention is shown in the accompanying drawing, in which:

Figure 1 is a side view of a flatiron having the improvement of this invention 40 mounted upon and attached to its rear end, parts of the handle and adjacent parts being broken away to show some of the details, and the switch being shown in its closed position.

Fig. 2 is a rear end view of the device shown in Fig. 1.

Fig. 3 is a fragmentary view showing only the rear part as viewed in Fig. 1, but with the iron tilted backward and the switch being open.

Fig. 4 is a fragmentary section on the line A—A of Fig. 1.

Fig. 5 is a fragmentary view, mainly in section on the line B—B of Fig. 3, but with the plug body in elevation.

55

Fig. 6 is a conventional diagram of the electrical connections.

In the embodiment shown in the drawings, the invention is applied to a flat iron 1 comprising a body part 2 and a handle 3. 60 The electric heater element 4 (Fig. 6) is contained in the lower part of the body member, as usual in devices of this character. Terminals 5 and 6 extend from the heater element to switching means at the upper 65 rear corner of the iron where a socket member 7 is provided in which the outer extremities of said terminals are disposed. A plug 8 is provided adapted for coaction with said socket and terminals, said plug being 70 provided with a two-conductor current supply cord 9, as understood in the art.

The socket comprises a frame or guide member 10 attached rigidly, at its lower and upper ends to the casing 11 of the flatiron body and the rear arm 3' of the handle 3 respectively. Said guide 10 is formed and adapted to serve as a protection for the terminals 5 and 6 and as a support for the plug. The upper end of said casing has forward and rear tips or guide lips 12 and 13 projecting somewhat and turned divergently so as to facilitate introduction of the plug. The forward or inner tip 12 serves as a supporting lug and is connected tightly over a 80 shoulder or tongue-like lug 14 struck backward on the handle arm 3'. A pair of downwardly projecting tips or lugs 15 are provided on the lower front side of the socket for interlocking with said body casing 11, which is provided with a pair of apertures or perforations 16 arranged to receive said lugs, and the lower ends of the latter are turned hookwise, preferably backward, so as to positively engage or hook 85 under the adjacent part of the casing 11 and interlock permanently therewith. By means of the said top and bottom members 12 and 15 the socket is held rigidly in place without the use of rivets or other fastenings.

100

The plug 8 is provided with a pair of contacts 17 contained in downwardly facing apertures 17', the latter being preferably in the form of slots adapted to receive

the terminals 5 and 6 when the plug is applied thereto. The contacts of each pair are connected as shown at 17" in Fig. 6.

Fastening means of automatic or partly 5 automatic character for locking the plug in its effective position are provided thereon, for which purpose a yielding latch member 18 in the form of a leaf spring is attached on the forward side of the plug. The fixed 10 end of the spring is apertured at 19 to receive the screw 20 by which it is fastened to the plug. In order to avoid any projection on the plug at this point the plug is formed with a depression 21 to receive the spring 15 and said screw 20. From this point the spring extends upward and thence curves forward and downward, the lower part lying normally adjacent to the front side of the plug where it is movable yieldingly away 20 from the plug when suitable force is applied. In connecting the circuit the plug is inserted by thrusting lengthwise down into the socket, the spring, however, at its outwardly turned free end being guided some- 25 what away from the plug and entering the uppermost aperture 22 in the handle arm 3', so that as the plug moves downward the lower end of the spring slides down on the front side of said arm in clasping relation 30 thereto.

In order that the plug may automatically be locked securely in place, said spring is provided with a rearward upwardly fac- 35 ing shoulder 23 on its rear side adjacent to its lower end, which shoulder is formed by striking back a tongue-like strip 23' integral at its lower end with said spring. Said shoulder 23 successively engages the forwardly turned lug or shoulder 12 in the upper aperture 22, the medial aperture 24, and the lowermost aperture 25 in the handle. 40

In order that the plug may be raised automatically for opening the switch upon release of the latch 18, resilient means are 45 supplied therefor in the form of a helical lifting spring 26, one end of which is fixed at 27 in the upper end of the plug coaxially with the latter, and the other end of which is provided with an outstanding peripheral 50 shoulder or ring member 28 to which the spring is permanently attached.

In applying the plug to the socket, the upper end of the spring 26 is hung upon the rearwardly projecting bracket 29, which is 55 provided on the upper end of the handle arm 3', the attachment of the plug being effected by sliding the shoulder member 28 over the slotted end of said bracket, the slot 30 being of open U-shape with the sides or 60 arms 29' pointing backward so as to receive the lifting spring and cord 9 when the latter are swung forward into place. Said bracket 29 may be held demountably by the threaded end of the handle screw 3''. The 65 resilience of said spring 26 renders it neces-

sary to push the plug downward forcibly by hand to its contact position. This is facilitated by the large hand ring or bearing 31 fitting loosely around the spring 26 and resting on the upper end of the plug. Said ring 31 may be made of wood or other suitable material.

When the plug has been forced to its effective position it is held or locked in place by the latch device 18 above described. In 70 order to release the plug, latch releasing means are provided in the form of a trip rod or plunger 32 extending diagonally downward and backward for coaction with the ironing board or other object operated 75 upon, or for direct manual movement inward against the lower end of the spring 18 so as to disengage the locking shoulder 23 from the upper edge or shoulder 25' of aperture 25.

Guide means are provided for the rod 32 on the rear end of the iron. For this purpose a bracket or plate 33, bent to an angular shape, is provided with an aperture 34 in one wing 33' which is disposed rearwardly to receive the rod. The other wing 33'' is laid against and secured to the back end of the iron, as by inwardly turned lugs 35 formed thereon at each side for attachment to the casing 11 by clenching in the 95 casing apertures 36. In order to limit the movement of the rod 32 a headed pin 37 is provided thereon for coaction with the slot 38 disposed parallelly in said wing 33' with respect to said rod. Said rearward wing 33' is curved somewhat, and the slot bearing part slants downward away from the iron so that when the iron is tipped back slightly the rod will be driven inward and the pin 37 will at the same time follow the 100 slot 38. The inner end of the rod 32 passes through apertures 39 and 40 in the rear and front of the socket wall 10 respectively, and between the insulators 5' and 6' in which the 105 terminals 5 and 6 are set.

The outer end of wing 33' is preferably bifurcated and the tips 41 are extended somewhat beyond the upturned tip 32' of rod 32, so that the iron may rest stably 110 when tipped back sufficiently to stand on end and rest on said tips 41 and the handle bracket 29, as will be understood. When so tipped back the iron rests on the triangular frame or stand comprised by the handle bracket 29 and the two guide bracket tips 41. 115

The operation for inserting the plug and locking the same may be summarized as follows: The operator grasps the plug in the right hand, holding the handle of the iron with the left hand and thrusts the lower end of the plug into the socket, the spring 18 entering the upper aperture 22. At this point in the operation, it is necessary to make sure that the shoulder 28 on the upper end of the lifting spring slides into place 120 125 130

on the upper side of the arms 29' on the bracket 29. The operator then forces the plug downward to its effective circuit closing position by pressure on the ring 31, 5 whereupon the latch 18 automatically engages the handle arm 3' at the shoulder 25' and holds the plug in place against the tension of the spring 26.

Whenever in using the iron the heat becomes excessive the plug may be released 10 and the circuit thereby broken merely by tilting the iron backward slightly so as to throw the release end of the trip pin 32 inward, by coaction of the outer end 32' with the ironing board or other surface on which the iron rests. As soon as the latch spring 15 18 is released the restoring spring 26 raises the plug and opens the circuit, the upward movement being arrested and limited by the latch shoulder 23 entering the aperture 24 and engaging the shoulder 24', in which condition the device may remain until more heat is required, whereupon the operator may again force the plug down to its effective 20 position where it will be again locked automatically by the latch 18.

The plug may be disconnected from the switch by an operation substantially the reverse of that described and connecting it in 30 place, the latch 18 being released either directly by hand or by means of the trip rod 32, whereupon the plug may be withdrawn, care being taken to hold the latch spring forward slightly so as to prevent engagement 35 of the latch shoulder 23 with the aperture 24 and the socket tip 12.

When the iron is not in use the plug may be left in its raised position, as shown in Figs. 2 and 5, though it may be entirely removed if preferred. Whenever it is desired 40 that the iron should become extra hot, and also when the current is first turned on, the iron may be disposed uprightly with the switch closed until it becomes sufficiently 45 hot, care being taken in setting the iron on end that the release pin 32 is not pushed in and the latch spring tripped.

Although but one specific embodiment of this invention has been herein shown and 50 described, it will be understood that numerous details of the construction shown may be altered or omitted without departing from the spirit of this invention as defined by the following claims.

55 I claim:

1. In a device of the character described, a supporting body member and handle, a switch socket member carried thereby, comprising a body of sheet metal formed in 60 tubular shape with lugs at each end adapted for attachment to said body member and handle respectively.

2. An electric flatiron having a pair of terminals at its rear end, a socket member 65 surrounding said terminals, a plug member

adapted to coact with said socket and terminals, means for supporting said plug yieldably and adapted to urge the plug to its open position, yielding lock means adapted to automatically fasten the plug in its closed 70 position and a diagonally disposed trip member extending backward and downward from the lower part of the socket and adapted to release said lock means by thrusting upward against the same. 75

3. An electric flatiron, comprising a body part and a handle therefor, a control device for the electric circuit, supporting means on said flatiron for the movable parts of said device, said body part and handle having 80 brackets respectively adapted to serve as said supporting means, said device comprising a plunger part carried by the handle bracket, and a trip member carried by the body bracket, stationary guide means being 85 provided for said plunger part.

4. A flatiron having a plug switch at its rear end, a rearward bracket also attached to the rear end of the iron and positioned to clear the ironing board when the iron is 90 in use, means urging the plug outward, means for locking the plug in its closed position, and trip means carried by said bracket adapted to release the locking means, said trip means having a contact part disposed downward from said bracket and adapted for actuation by contact with the ironing board when the iron is tilted backward. 95

5. A flatiron having a plug switch at its rear end, a rearward bracket also attached 100 to the rear end of the iron and positioned to clear the ironing board when the iron is in use, means urging the plug outward, means for locking the plug in its closed position, and trip means carried by said bracket adapted to release the locking means, 105 said trip means having a contact part disposed downward from said bracket and adapted for actuation by contact with the ironing board when the iron is tilted backward, said bracket extending beyond the trip means and being adapted to serve as a support for the flatiron when stood upright on its rear end. 110

6. A flatiron having a spring actuated 115 plug switch at its rear end adjacent to the rear side of the rear handle arm, said plug having a spring latch attached to its upper end and extending downward toward its tip, said arm being apertured to receive said latch and having a pair of shoulders one above the other beneath said aperture, and said latch at its free lower end being formed and adapted to coact with and releasably engage said shoulders at its closed and open 120 positions respectively.

7. An electric ironing implement, comprising a plug switch, upwardly acting resilient means for supporting the plug, means for holding the plug down, and a forked 125 130

4
bracket on the handle of said implement having a U-shaped opening to receive said means demountably, said means being in the form of a helical tension spring attached at its lower end to said plug and at its upper end having a shoulder adapted to seat on the arms of the forked bracket.

5 8. An electric ironing implement, comprising a plug switch, upwardly acting resilient means for supporting the plug, means for holding the plug down to close the switch, a forked bracket having a U-shaped

opening to receive said means demountably, said means being in the form of a helical tension spring attached at its lower end to 15 said plug and at its upper end having a shoulder adapted to seat on the arms of the forked bracket, means for releasing the plug by tilting the implement, and a current supply cord disposed within said spring and 20 connected to said plug.

Signed at Chicago this 14th day of March, 1917.

FRANK A. SCHULTZ.
